UNITED STATES PATENT OFFICE.

EUGENE R. CARICICOFF, OF SCHENECTADY, NEW YORK, ASSIGNOR TO GENERAL ELECTRIC COMPANY, A CORPORATION OF NEW YORK.

SERIES-PARALLEL CONTROL SYSTEM.

1,110,039.

Specification of Letters Patent. Patented Sept. 8, 1914.

Application filed April 15, 1913. Serial No. 761,241.

To all whom it may concern:

Be it known that I, EUGENE R. CARICICOFF, a citizen of the United States, residing at Schenectady, in the county of Schenectady, State of New York, have invented certain new and useful Improvements in Series-Parallel Control Systems, of which the following is a specification.

This invention relates to the control of electric motors and more particularly to the control of a plurality of motors operating on what is known as the series parallel system of control.

One of the objects of my invention is to provide an improved series parallel control system for electric motors in which the electromagnetic switches for short circuiting the resistance are of the type in which the operating windings are in the motor circuit. In the use of the series parallel control system it has been customary to employ a single resistance which is first connected in the circuit of the motors in series position and is then connected in series with the motors in parallel position. With this arrangement it is essential that the switches shall drop open upon being deenergized before the parallel connections are made, otherwise the motors may be connected in circuit without the protecting resistance. This difficulty is sometimes overcome by the use of interlocking contacts for insuring the proper sequence of operation.

In carrying out my invention I employ a resistance for the motors in the series position which is separate and distinct from the resistance employed in the parallel position of the motors. The resistance is short circuited by the electromagnetic switches and then left short circuited while the other resistances are connected in circuit with the motors in the parallel position. With my arrangement the motors go through the complete cycle from the series to the parallel position employing electromagnetic switches having operating windings in the motor circuit for short circuiting all of the resistances, without opening the motor circuit in making the transition, and the use of interlocking contacts on the resistance switches may be entirely dispensed with.

Other objects and purposes of my invention will appear in the course of the following specification in which I have shown my

invention embodied in concrete form for 55 purposes of illustration.

In the accompanying drawings, Figure 1 illustrates one form of my invention, and Fig. 2 illustrates a modification thereof.

Referring to Fig. 1 of the drawings, A and A' represent the armatures of two motors to be controlled and F, F' the series fields of the motors. R, R, R represent the sections of resistance which are to be connected in circuit with the motor in the series position and are known as the series resistance. R', R', R' are sections of resistance to be connected in series with the armatures A' and A respectively, in the parallel position. S and S' are the two electromagnetic switches for short circuiting the resistance R, while similar switches S², S³, S⁴ and S⁵ short circuit the resistances R' and R' respectively. The particular construction and arrangement of these electromagnetic switches forms no part of my present invention, although the characteristic features of these switches are of importance in the operation of my system. These switches have their operating windings in the motor circuit and have the characteristic that they are held in the open position when the current is relatively high and do not close until the current falls to a predetermined value.

The particular form of switch which is diagrammatically illustrated in the drawing is covered by a prior application of Edwin J. Murphy, Serial No. 608,652, filed February 15, 1911.

B and C are two contactors of the ordinary type for controlling the motor circuit. These contactors are controlled by the master controller M, contactor B being energized in the first position and contactor C in the second position of the master controller.

D represents an electromagnetic switch for changing the connections of the motors from series to parallel. The particular construction of this switch forms no part of my present invention but is covered by a separate application filed by me, Serial No. 756,399, filed March 24, 1913. This switch consists of a magnetizing winding 10 adapted to be connected in the motor circuit and a core or plunger 11 having pivoted thereto a switch arm 12. The core 11 is connected

to the central point of the switch arm 12 and the latter coöperates at either end with the contacts 13, 14. A spring 15 presses the left hand end of the lever into engagement with the contact 14. When the winding 10 is energized the core is raised and with it the lever 12. During the first portion of the movement, the contact 14 acts as a fulcrum for the lever until the right hand end of the contact is brought into engagement with the contact 13. When the engagement is made with the contact 13 the latter becomes the fulcrum so that further movement of the core compresses the spring 15 and moves the lever 12 out of engagement with the contact 14.

The circuit of the winding 10 is controlled by contactor T which operates in the same manner as the contactors, S, S', S², &c., with the exception that the moving contact is not connected with the operating winding but is insulated from the switch structure. The switch, therefore, is held open when the current is high and closed when the current falls to a predetermined value. The winding of this contactor is energized when the resistance contactor S' closes. This contactor T will not therefore close the circuit of the winding 10 until the current falls to a predetermined value after cutting out the last section of resistance R. The closure of this switch T is also controlled by the master controller in the third position. The contacts of the contactor T are held open by the latch 16 so that even though the resistance is all cut out and the current has fallen to a predetermined value, the contactor T will not close to establish the parallel position until the master controller has moved to the third position and electromagnet 17 is energized, which attracts the latch 16 and moves it against the tension of spring 16' to release the contact of the contactor T.

As thus constructed and arranged the operation of my system is as follows, assuming the parts in the position shown. When the master controller has moved into the first position *a*, contactor B will be energized, thereby closing the motor circuit from the trolley to the contacts of contactor B, resistances R, armature A, field F, through the contact 14 and lever 12 of switch D, armature A' and field F' to ground. In this first position of the master controller, therefore, the motors are in series with all the series resistance in circuit. When the master controller is moved to the position *b* the contactor C is energized which upon closing short circuits the first section of resistance R through the operating winding of the switch S. The cutting out of a section of resistance R causes a rush of current through the motor circuit and winding of the switch S. All the switches S are constructed, in a manner now well understood, so that they

will not close at the first rush of current but only after the current has dropped to a predetermined lower value. When, however, the motors speed up so as to reduce the current to a predetermined value the switch S 70 will close, thereby short circuiting the second section of resistance R and connecting the operating winding of the switch S' in circuit. In like manner, when the switch S' closes the last section of resistance R is short circuited through the winding of the contactor T. The two motors are now connected in series through the contacts of the contactors B and C, S and S', and through the winding of the contactor T. If now the master controller is moved into the position *c* the wire leading to the electromagnet 17 will be connected to trolley so that the latch 16 will be moved to release the contact of the contactor T, which will therefore close as soon as the current in the motor circuit drops to a predetermined value and thereby close the circuit of the winding 10 of parallel switch D. The winding 10 being energized, the parallel connection of the motors will first be made at the contact 13, and the series connection then broken at the contact 14. The motor circuit now divides into two parallel paths, one leading from trolley through the contacts of the contactors B, C, S, S' and the winding of contactor T, armature A, field F, contacts of contactor T, winding 10 of switch D, thence through the winding of switch S' and resistances R² to ground, and the other leading through the contacts of contactor B, resistances R' R' to the winding of the switch S', contact 13, armature A' and field F' to ground. It will be noted that the current to motor A is still supplied through the contacts of the series switches S S' so that the latter must be maintained in closed position. In other words, successful operation does not depend upon the opening of the switches S and S'. The first rush of current upon connecting the motors in parallel causes the switches S' and S' to hold open until the motors speed up and reduce the current, whereupon the switches S' and S' close and short circuit the first section of resistance R' and R' respectively. In like manner switches S² and S² close and short circuit the last section of resistance, thereby connecting the two motors in parallel with all resistances short circuited.

In Fig. 2 I have shown a modified form of my invention in which one of the parallel resistances is also used in series. In order to bring about this result the arrangement of the switches B' and C', corresponding to the arrangement of switches B and C of Fig. 1, is modified. The contactor C' is provided with interlocking contacts 18 and 19 and the switch S' corresponding to S, Fig. 1, is provided with interlocking contacts 20 which are closed when the switch closes.

With this arrangement one of the switches for controlling the resistances R' is dispensed with, since the function is accomplished by a second operation of the switch B' . The operation of this form of my invention is as follows: When the master controller M is moved to the first position the contactor B' is energized through the interlocking contacts 19 of the contactor C' . This closes the motor circuit from the trolley through the contacts of the contactor B' , through the resistance R' , thence through the resistances R , armature A , field F , contact 14 of the parallel switch D , armature A' , field F' to ground. When the controller is moved to the second position shown at b , contactor C' is energized which closes the interlocking contacts 18 and opens the interlocking contacts 19 to deenergize the contactor B' . The closing of the switch C' short circuits the resistance R' and completes a circuit from trolley through the contacts of contactor C' , through the winding of switch S , resistance R , armature A , field F , contact 14, armature A' , field F' to ground. The remaining sections of resistance R are cut out of circuit as described above. When the controller is moved to the third position c the parallel switch D closes as before, the connection of the motors being as follows: From the trolley through the contacts of the contactor C' , through the winding of contactor S , thence through two paths, one through the contacts and windings of the switches S' and S^2 , contactor T , armature A , field F , thence to the contacts of contactor T , winding of parallel switch D to the switch S^4 , resistances R^2 to ground, while the other path is from the winding of the switch S , through the resistances R' , winding of the switch S^3 , contact 13 of switch D , armature A' , field F' , to ground. The first rush of current upon connecting the motors in parallel causes the switches S^2 and S^4 to hold open until the motors speed up to reduce the current, whereupon these switches close and short circuit the first section of resistance R' and R^2 respectively. When the switch S^4 closes it short circuits the section of resistance R^2 through the winding of switch S^6 and when the current drops to a proper value the switch S^6 will close and short circuit the second section of resistance R^2 . The closing of the switch S^6 closes the interlocking contacts 20 which completes a circuit through the wires 21 and 22 to the contactor B' independently of the contactor C' . The closing of the contactor B' short circuits the second section of resistance R' and places the two motors in parallel across the line. Contactor B' , therefore, serves the double purpose of closing the motor circuit in the first position of the master controller and of acting as a resistance switch to cut out section of resist-

ance R' in the last position of the master controller. The interlock 18 on contactor C' insures that the two controllers B' and C' will both drop out at the same time when the controller is returned, thereby preventing the current from being broken on some of the other contactors which are not designed to break current. Aside from the use of the resistance R' in the series position this system operates practically the same as the system shown in Fig. 1. The advantage of the use of this resistance in the series position is that a very slow speed may be obtained in the first position of the master controller without unduly increasing the amount of resistance.

While I have described my invention as embodied in concrete form and as operating in a specific manner for purposes of illustration, it should be understood that I do not limit my invention thereto, since various modifications thereof will suggest themselves to those skilled in the art without departing from the spirit of my invention, the scope of which is set forth in the annexed claims.

What I claim as new and desire to secure by Letters Patent of the United States, is—

1. In a series parallel control system, a pair of electric motors, electromagnetic means for connecting said motors in series or in parallel, a resistance for the motors in the series position, additional resistances one for each motor in the parallel position, and electromagnetic switches having their operating windings in the motor circuit for controlling said resistances.

2. In a series parallel control system, a pair of electric motors, resistances for the motors, electromagnetic switches having their operating windings in the motor circuit for short circuiting said resistances, and means whereby said motors are connected first in series and then in parallel with a resistance in circuit in each position without opening the motor circuit.

3. In a series parallel control system, a pair of electric motors, a series resistance, a master controller, means controlled thereby for connecting said motors and resistance in series with each other, electromagnetic switches having their operating windings in the motor circuit for cutting said resistance out of circuit, means for connecting the motors in parallel through the closed contacts of said resistance switches, a resistance in series with each motor in the parallel position, and electromagnetic switches having their operating windings in the motor circuit for cutting out said resistances.

4. In a series parallel control system, a pair of electric motors, a resistance for the motors in the series position, a resistance for each motor in the parallel position, electromagnetic switches having their operating windings in the motor circuit for short cir-

cuiting said resistances, and means whereby said motors are first connected in series with the series resistance in circuit and then in parallel with a resistance in series with each motor without opening the motor circuit.

5. In a series parallel control system, a pair of electric motors, a resistance for the motors in the series position, a resistance for each motor in the parallel position, electro-
10 magnetic switches having their operating windings in the motor circuit for short circuiting said resistances, and an electromagnetic switch for connecting the motors in parallel with a resistance in series with each motor through the closed contacts of the series resistance switches.

6. In a series parallel control system, a pair of electric motors, a series resistance, a

master controller, means controlled thereby for connecting said motors and resistance in series with each other, electromagnetic 20 switches having their operating windings in the motor circuit for short circuiting said resistance, a resistance for each motor in the parallel position, an electromagnetic switch for connecting the motors in parallel each 25 with a resistance in circuit therewith through the closed contacts of the series resistance switches.

In witness whereof, I have hereunto set my hand this 14th day of April, 1913.

EUGENE R. CARICHOFF.
